Plastics, Inc., New York, N.Y., a corporation of New York

Filed Oct. 22, 1965, Ser. No. 87,769

Term of patent 14 years

(Cl. D4—4)

FIG. 1

FIG. 2

FIG. 3

FIG. 4

FIG. 5

FIG. 1 is a top view in perspective of the baby bath, forming the subject matter of my new design;

FIG. 2 is a bottom elevation of the baby bath;

FIG. 3 is a side elevation of the baby bath;

FIG. 4 is an elevation of one end of the baby bath; and

FIG. 5 is an elevation of the other end of the baby bath.

The dominant features of my design reside in the portions shown in full lines, and the handle shown in broken lines in FIG. 1 is omitted in the other views for convenience of illustration.

I claim:

The ornamental design for a baby bath, as shown and described.
